MAGNETIC COUPLING

Georg Neumann, Berlin, Germany

Application September 28, 1935, Serial No. 42,658
In Germany October 5, 1934

3 Claims. (Cl. 74—210)

This invention relates to a magnetic coupling or relay and has particular reference to a magnetic coupling for use in measuring, recording and like instruments.

5 It is an object of the present invention to provide a magnetic coupling or relay which permits reciprocal movement of an associated armature, under control of electrical currents acting upon coils forming part of the coupling.

10 Another object of the invention is to produce a relay which is adapted to carry out controlling or adjusting movements with an increased mechanical power under the control of comparatively small electrical currents, more particularly fed from a measuring instrument or microphone.

15 With these and other objects in view, as may become apparent from the within disclosures, the invention consists not only in the structures 20 herein pointed out and illustrated by the drawings, but includes further structures coming within the scope of what hereinafter may be claimed.

The character of the invention, however, may 25 be best understood by reference to certain of its structural forms, as illustrated by the accompanying drawing in which—

Fig. 1 is a diagrammatic view showing an embodiment of my novel coupling, in a front elevation, as applied to a sound recording apparatus.

Fig. 2 is a side view of the magnetic coupling shown in Fig. 1.

Figs. 3 to 6 are modified circuit diagrams for 35 energizing my novel magnetic coupling.

Figs. 7 and 8 are characteristic curves of thermionic valves for use in connection with my novel magnetic coupling.

Similar reference numerals denote similar 40 parts in the different views.

Referring now to the drawing in greater detail, and first to Figs. 1 and 2, it will be seen that the magnetic relay comprises two disks 16 and 17 of a suitable magnetisable or magnetic 45 material mounted on a common shaft 31 which is rotated by means not shown in the drawing. The disks 16 and 17 are magnetically interconnected by a central part 22 and adapted to be energized by stationary coils 10 and 14 surrounding the upper and lower portions of the disk 16, respectively. Armature members 18 and 19 of a 50 fork 20 engage the opposite portions of disks 16 and 17, under slight resilient friction, thus making up two closed magnetic circuits 17, 22, 16, 18 and 17, 22, 16, 19, respectively.

It will thus be noted that it is possible, by suitable energizing of the two coils 10 and 14, to control the amount of friction between the disks 16, 17, and the armature member 18 on the one hand and between the disks 16, 17 and the armature member 19 on the other hand so that, when the amounts of friction at 18 and 19 are not exactly similar, the fork 20 will be moved in a direction depending on the frictional ratio and the direction of rotation of the shaft 31.

10 While my said novel magnetic relay may be used for a wide variety of different purposes of use, one application of the same which is representative for the usefulness of my relay will be hereinafter described by way of example.

15 Referring again to Fig. 1, showing my novel relay installed in a sound recording apparatus, it will be seen that a microphone 1 is exposed to the sound the intensity of which is to be recorded, and, together with the associated amplifier 2, 20 makes up means for transforming sound into electrical output. A potentiometer 3 the resistance value of which along its length is preferably provided to grow in accordance with a logarithmic curve, receives its input current from said sound 25 transforming means, and is provided with a sliding contact or movable member 4. One end of the potentiometer 3 and the sliding contact 4 are connected to the input terminals of a second amplifier 5, the output terminals of which are 30 connected to the grid 6 and the cathode 7 of the electron valve 8 acting as an audion valve, by means of the condensers and resistances necessary for the audion circuit. In the anode circuit of the valve 8 there is inserted, in series to 35 the anode battery 9, the winding 10 forming part of the above described magnetic coupling. One terminal of the winding 10 is connected to the cathode 7 of the audion 8, while the other terminal thereof is connected to the grid 11 of a 40 second electron valve, in the anode circuit of which the second winding 14 of the magnetic coupling is interpolated in series with an anode battery 13. The cathodes of the two valves 8 and 12 are connected in parallel in the usual 45 manner and are fed from the heating battery 15. A pen or stylus 21 mounted on the fork 20 draws a curve on a paper strip or the like running over the rollers 23 and 24, which curve represents 50 the sound intensity values received by the microphone. The driving arrangement for the paper strip is not shown, for the sake of clearness.

55 The function of my novel magnetic relay will now be described in connection with the oper-

ation of the said sound recording device as follows:

If no sound acts on the microphone 1, the sliding contact 4 and the pen 21 may for instance be in their left hand end position, so that the input terminals of the amplifier 5 are in connection with the end terminals of the potentiometer. In this working condition the maximum anode current flows in the anode circuit of the valve 8, which energises the coil 10 and consequently magnetises that part of the disc 16 which happens to be the bottom part at the time. The potential drop obtaining in the coil 10 is impressed as a negative grid bias on the valve 12, so that the anode circuit of this valve and consequently also the excitation coil 14 is dead. By reason of this the rotary discs 16 and 17 of the magnetic coupling, which are magnetised in their bottom parts only, tend to im- 10 part a movement to the fork 20 in a left hand direction, while the fork cannot carry out this movement as the sliding contact 4 and the pen 21 as mentioned above are already in their left hand end position, defined by a stop or the like, 20 as indicated at 38.

Now if a sound of a definite intensity impinges on the microphone and consequently generates currents in the microphone and thus a potential on the potentiometer, then the grid 6 becomes charged through the sliding contact 4 and the amplifier 5, which causes the anode current of the valve 8 to drop, whereby the excitation of the coil 10 is weakened and the potential of the grid of the second valve 12 altered, so that now a current arises in the anode circuit of this valve, which energises the coil 14 and thereby magnetises the top part of the discs 16 and 17. Since the magnetisation of the lower disc parts is thus decreased and that of the top parts increased, 30 a push in the right hand direction is exerted on the fork 20 which lasts for so long until, by reason of the action hereafter described, the magnetisations created by the coils 10 and 14 balance each other in their action on the legs 18 and 19. By 40 reason of the push to the right exerted on the fork 20 the sliding contact 4 and the pen 21 are pulled to the right together with the fork. By this movement the contact 4 taps off a constantly dropping potential on the potentiometer 3, so that the biasing potential on the grid 6 changes again in the opposite sense, and consequently the anode current flowing through the coil 10 rises again. But at the same time the bias potential of the grid 11 is also changed again. Conse- 50 quently the anode current of the second valve 12 and with it the energising current of the coil 14 is again weakened, and these changes continue for so long until the currents flowing in the coils 10 and 14 balance each other in their 60 actions on the fork 20, and the sliding contact 4 and the pen 21 assume their positions corresponding to the sound intensity, around which they execute only small pendulous movements as long as the sound intensity remains unaltered. 70 If the strength of the sound acting on the microphone decreases again, then the anode current in the anode circuit of the valve 8 rises so that the excitation of the coil 10 is strengthened. Simultaneously the anode current of the valve 12 drops and with it the energising current of the coil 14. This causes a push towards the left to be exerted on the fork so that it is moved to the left together with the sliding contact 4 and the pen 21, into the position corresponding to the 75 now obtaining sound strength, which position

will coincide with the left end position if a pre-determined minimum or zero sound volume acts upon the microphone.

Each time when the sliding contact 4 and the pen 21 are in positions corresponding to the sound strength at the time, the forces exerted by the coils 10 and 14 on the fork 20 neutralize each other. With a symmetrical design of the magnetic coupling and its excitation coils, this will be the case, when the same amount of current flows in both coils. When the number of turns of the coils are different then the equilibrium is obtained at that current proportion which gives the same number of ampere turns. It is evident that in each position of equilibrium of the fork 20 a quite definite proportion of current strengths reign in the anode circuits of the valves 8 and 12, and as the grid bias potential of the valve 12 is controlled only from the anode current circuit of the valve 8, this proportion between the anode currents only occurs at a quite definite value of the biasing potential of the grid 6, that is to say at a quite definite value of the input potential of the amplifier 5 tapped off by the sliding contact 4.

It is therefore evident that the sliding contact 4 always takes up such a position that the input potential of the amplifier 5 and the current and potential proportions of the circuit elements interpolated after it have in the constant condition the same value.

Figures 3 to 5 show a few further circuits for the excitation of the coils for the magnetic coupling. In the circuit according to Figure 3 the coil 10 is interpolated in the anode circuit of the first valve 8 in series with the anode battery 9 which is common to both the valves, as is also a resistance 28. The grid 11 of the second valve 12 is connected through a resistance 27 with a sliding contact 28 with which a source of electricity, such as for instance a battery 29 is connected in parallel, to a middle tapping point between the coil 10 and the anode of the first valve 8. The excitation coil 14 is interpolated between the anode of the second valve 12 and an intermediate point between the exciting coil 10 and the battery 9. In principle the functioning of this circuit is similar to that of Figure 1. The sliding contact 28 is so adjusted, that no anode current flows in the second valve 12 when the first valve carries its full anode current. But as soon as the anode current of the first valve drops and thereby causes a decrease of the excitation of the coil 10 the bias potential of the grid 11 is altered so that an anode current begins to flow in the second valve 12, which excites the coil 14.

Figure 4 shows a circuit with only one valve 8 in the anode circuit of which the excitation coils 10 and 14, the anode battery 9 and a resistance 26 are connected in series. A further source of electricity (battery 30) and a resistance 31 are connected in parallel to the second excitation coil 14. The potentials of the batteries and the resistances 26 and 31 are so chosen that when the full anode current flows in the valve 8 the coil 14 is without current. As is evident the coil 14 gets so much more current, the greater the anode current of the valve 8 is and the further the current in the coil 10 drops.

In the circuit according to Figure 5 there is also only one valve, but a double grid valve 32 is used, the coil 10 is in the anode circuit of the valve in series with the anode battery 9 and the resistance 26. The coil 14 is in circuit with the 75

filament screening grid of the valve and is connected at a tapping point between the coil 10 and the battery 9. If a full anode current flows in the valve 32, i. e. if the coil 10 is at its maximum excitation, the current in the circuit of the filament screening grid is small, i. e. the coil 14 is only a little excited. When the anode current and the excitation current of the coil 10 drops then the current in the filament screening grid and the coil 14 rises.

In the circuit according to Figure 6 which is specially suitable for connection to the mains, the rectification does not occur in the final stage, but in an intermediate stage, two amplifying valves being provided behind the rectifying valve, the excitation coils being interpolated in the circuit of the amplifying valves in such a manner, that when the excitation current of one of the coils drops the current of the other rises.

The amplifier 5 is shown here as an amplifying valve, the output terminals of which are connected to the cathode and the grid of a rectifying valve 33, which works with anode current rectification or anode bend rectification. A heating transformer 35 with its secondary winding tapped at the middle is used as a source for the cathode heating current, whilst the anode potentials for the individual valves are supplied by the terminals marked "150 V" and "200 V", which in their turn are fed from the member connecting the apparatus to the mains or power supply. The terminals for 200 volts which lie in the anode circuit of the amplifying valve 5 are bridged over by a subdivided resistance 34 from the tappings of which the anode potential for the valve 5 and the grid biasing potentials for the rectifying valve 33 and also for the second final valve are taken. In the anode circuit of the rectifying valve 33 there is interpolated a subdivided resistance 36, the tap of which is connected with the middle point of the heating transformer 35. The portions of the resistance 36 which are bridged over by the condensers 31, lie in the grid circuits of the amplifying valves 38 and 39, of which the first, 38, works without any grid bias, whilst the second valve 39 has thereby a negative grid bias imparted to it, due to the fact that the corresponding part of the resistance 36 is not connected direct, but through a suitably chosen part of the potential dividing resistance 34, to the grid of the valve 39. The excitation coils 10 and 14 are interpolated in the anode circuits 38 and 39. In this case the anode currents supplied by the amplifying valve 5 are rectified by the valve 33 and amplified by the valves 38 and 39. By reason of the circuit of the valves 38 and 39 shown and their functioning with or without grid bias a similar result as

that obtained with the circuit according to Figure 3 is attained, i. e. that the coil 14 is less excited when the coil 10 is highly excited, and vice versa.

According to the circuit diagrams shown in Figures 1 and 3 to 5, the valve 8 works in a rectifying circuit, the grid being however somewhat at a negative potential by reason of the battery in series with the resistance in the grid circuit. This is brought about for the purpose of effecting a starting of the grid current only, when the positive wave half of the potential impressed on the grid exceeds a certain value, so that the anode current has a non-linear characteristic curve or increasing value relatively to the impressed potential. Figure 7 shows the diagram of this circuit, in which J_a designates the anode current and J_g the grid current. As can be seen, the working point A is somewhat displaced by the negative grid bias potential.

Instead of working with an audion circuit it would also be possible, in Figures 1 and 3-5 to work with anode current rectification, similar to the circuit shown in Figure 6. But in such a case it is preferable to use a greater grid bias potential than usual, so that the working point A (Figure 8) lies far beyond the beginning of the anode current line J_a , in order to ensure that a non-linear increase of the direct current component of the anode current follows a non-linear characteristic curve.

What I claim is:—

1. A magnetic coupling comprising a constantly driven member including two rotating discs, two stationary exciting coils surrounding opposite portions of only one of said discs and adapted for variable and simultaneous energization, and a movable forked armature the legs of which engage on opposite sides of said discs so as to be controlled in accordance with the energization of said coils.

2. A magnetic coupling comprising a rotatable member including two rotating discs, stationary exciting coils associated with only one of said discs and adapted to be variously energized, and a forked armature engaging the peripheries of said discs for movements in accordance with the energization of said coils.

3. A magnetic coupling comprising a rotatable member including two rotating discs, stationary exciting coils associated with opposite portions of only one of said discs and adapted to be variously energized, and a reciprocating armature having portions engaging on opposite sides of said discs and reciprocated thereby in accordance with the energization of said coils.

GEORG NEUMANN.
